REFRIGERATING APPARATUS

Andrew A. Kucher, Oakwood, Ohio, assignor to
General Motors Corporation, Dayton, Ohio, a
corporation of Delaware

Application October 28, 1940, Serial No. 363,093

9 Claims. (Cl. 62—102)

This invention relates to refrigerating apparatus and more particularly to household refrigerators.

Inasmuch as the freezing compartment is used considerably less than the food storage compartment in household refrigerators, it is desirable to place the freezing compartment beneath the food storage compartment so that the food storage compartment will be more accessible. This, however, prevents natural circulation.

It is an object of my invention to provide an efficient and simple means for cooling the food storage compartment when it is located above or adjacent the freezing evaporator.

It is another object of my invention to provide an efficient means for transferring heat between a primary evaporator and a food storage compartment located above or adjacent the primary evaporator.

It is another object of my invention to provide an efficient means for moving a fluid into heat exchange relation with a heat transfer means.

It is still another object of my invention to provide a noiseless fan requiring no lubrication.

It is another object of my invention to provide a vibrating reed-type fan.

Further objects and advantages of the present invention will be apparent from the following description, reference being had to the accompanying drawings, wherein a preferred form of the present invention is clearly shown.

In the drawings:

Fig. 1 is a vertical sectional view through a household refrigerator cabinet embodying one form of my invention;

Fig. 2 is a vertical sectional view of a refrigerant liquefying unit embodying another form of my invention;

Fig. 3 is a top view of the liquefying unit shown in Fig. 2;

Fig. 4 is a horizontal sectional view of one of the fan means shown in Fig. 1;

Fig. 5 is a vertical sectional view of a modified form of fan means;

Fig. 6 is a sectional view of the fan means shown in Fig. 4 taken along the line 6—6 of Fig. 7; and

Fig. 7 is a sectional view taken along the line 1—1 of Fig. 6.

I have shown a household refrigerator cabinet with a food compartment inner liner located above the freezing compartment. An air passageway surrounds both compartments and an electrically operated vibrating reed-type fan is provided for circulating the air through the pas-

sageway in order to transfer the heat from the walls of the food compartment inner liner to the outer surfaces of the freezing compartment. An electrically operated vibrating reed-type fan is also used for circulating air over the surfaces of the condenser. In another form, the vibrating reed-type fan is mounted upon the sealed unit and is operated by the vibrations of the sealed unit for discharging air over the condenser surfaces.

Referring now to the drawings and more particularly to Fig. 1, there is shown a household refrigerator cabinet 20 containing a food storage compartment inner liner member 22 enclosing a food storage compartment 24. At the bottom of the food storage compartment inner liner 22 is a freezing compartment 26 which is separated from the food storage compartment 24 by a dividing wall or partition 28 of some suitable insulating material. If desired, this partition wall may be vertically movable in order to change the relative sizes of these two compartments. The freezing compartment 26 is enclosed upon the bottom and two sides by a primary evaporating means 30 which is normally maintained at freezing temperatures. Insulating means 32 surrounds the food compartment inner liner member 22 and the primary evaporator 30 but is spaced therefrom in order to provide an air passage 34 which extends in a complete circuit entirely around the top side and rear walls of food compartment inner liner member and bottom, rear and side walls of the primary evaporator 30. Both the freezing and food compartments are sealed from the air in the passage 34 at all points.

This cabinet arrangement is desirable since it places the food compartment at a much more convenient height. Since the food compartment is used much more frequently than the freezing compartment, there is a distinct gain in convenience by this arrangement. However, this arrangement makes it impossible to use natural convection for cooling the food storage compartment 24 by the primary evaporator 30.

In order to overcome this difficulty in a very efficient manner, I have provided a vibrating reed-type of fan 38 which is electrically driven. The air located in the passage 34 in the portion 50 surrounding the food storage compartment 24 is drawn by this fan downwardly beneath the primary evaporator 30 and discharges the air transversely beneath the primary evaporator 30 so that it is cooled and rises to displace the air drawn downwardly by the fan. By this circu-

lation heat is transferred from the outer surface of the liner member 22 to the outer surface of the evaporator 30. Only a comparatively small amount of air circulation is required for this purpose and this air circulation keeps the outer walls of the inner liner member 22 cool, preferably at a temperature of between 35° and 40° F.

There is little or no air circulation in the food storage compartment 24 since the partition 28 has its insulating value so proportioned that its upper surface is maintained at a temperature slightly below the remaining wall surfaces of the compartment 24. In this way, the walls of the compartment 24 are kept comparatively cold and air circulation within the compartment 24 is substantially prevented. Since the food compartment 24 is cooled through its walls at a comparatively high temperature, a high humidity will be maintained in the compartment and since there is little air circulation, dehydration of the foods stored therein will be substantially prevented.

The primary evaporator 30 forms a part of a primary refrigerating system which includes the motor-compressor unit 42 containing an electric motor and a compressor for withdrawing evaporated refrigerant from the primary evaporator 30 through the suction conduit 44. The sealed unit 42 discharges the compressed refrigerant into an air cooled condenser 44 which is connected by a liquid supply conduit 46 with a restrictor 48 for controlling the flow of liquid refrigerant into the primary evaporator 30. The operation of sealed unit 42 is controlled by a thermostat switch 52 operated in accordance with the temperature of a thermostat bulb 54, mounted in direct contact with the primary evaporator 30 in order to normally maintain the primary evaporator 30 at freezing temperatures. An electric vibrating reed-type fan 38 is connected by the conductors 56 to the motor circuit 58. It may be connected in series with the sealed unit 42 so that it will cycle with the sealed unit 42, but I find it preferable to connect this fan in parallel with the sealed unit 42 and the switch 52 so that it will operate continuously. I also provide an electrically operated vibrating reed-type fan 60 for discharging air over the heat transfer surfaces of the condenser 44. This fan may be connected by the conductors 62 in series circuit relation with the sealed unit 42. This type of fan, when desired, may be made in such a way that substantially no voltage is required for its operation.

Referring now to Figs. 4, 6 and 7 for a more complete disclosure of one form of this type of fan, there is shown a sheet metal shroud 66 having an inlet 68 and a bell-shaped outlet 70. The outlet 70 is positioned directly adjacent the condenser 44 so that it discharges directly through the central portion of the condenser parallel to the fins. Within the shroud there is provided a vibrating blade 72 riveted to the ends of a pair of vibrating reeds 74. These reeds 74 as well as the blade 72 are made of high quality very thin spring steel. The opposite ends of the reeds 74 are clamped by the clamping blocks 76 and the nuts 78 to the inverted T-shaped pole piece.

Surrounding the pole piece 80 is an electromagnet coil 82. The pole piece 80 is provided with a hooked end 84 which terminates slightly to one side of the natural position of the blade 72. This hooked end 84 is a permanent magnet which functions in conjunction with the elec-

tromagnet coil 82 to vibrate the blade 72. The anchoring ends of the reeds 74 are slotted so that the length of the reeds may be adjusted in order that the natural period of vibration of the blade assembly is tuned to the frequency of the alternating current supplied to the coil 82.

The coil 82 may be either a series coil in which it is connected in series with the electric motor in the sealed unit or it may be a high resistance 10 coil which may be connected directly across a supply line. When the reed assembly is properly tuned, only a very small amount of current is required to vibrate the reed. The reed assembly, of course, will vibrate even though not properly tuned but the amplitude of the vibration and the efficiency of air movement is greatly increased when the reed assembly is tuned to the frequency of the alternating current. The hooked permanent magnet 84 aids in starting the blade to vibrate and increases the amplitude of the vibrations of the blade 72. The vibrations of the blade 72 draw the air in through the inlet 68 and discharge the air through the bell-shaped end 70 of the shroud 66 so that the air passes through the condenser 44. The vibrating reed fan 38 is similar to the fans shown in Figs. 4, 6 and 7, excepting that the shape of the shroud is flattened so that it fits the space provided beneath the primary evaporator 30.

Fig. 5 shows another form of vibrating reed fan which may be applied to the heat transfer member 44 or which may operate beneath the primary evaporator 30 like the fan 38. This vibrating reed fan shown in Fig. 5 includes a vibrating reed 202 which is anchored at its lower end by being held between the plates 204 and 206 which in turn are riveted to a flanged base member 208. Attached to the vibrating reed 202 is a permanent magnet 210 of the bar type. This permanent magnet 210 is fastened to the vibrating reed 202 by a yoke 212 which has its ends passing through the plates 214 located on opposite sides of the reed 202. The ends of the yoke 212 are spun over to form rivet heads in order to fasten the bar magnet 210 firmly to the reed. The end of the bar magnet 210 terminates between the ends of the upper and lower pole pieces 216 and 218 of an electromagnet 220. This electromagnet 220 is fastened to the base 208.

This electromagnet may be connected in series or in parallel with the sealed unit 42. When alternating current is applied to the electromagnet 220 it will attract and repel the permanent magnet 210 to cause the reed 202 to vibrate. The reed is so proportioned as to length, width, thickness and character of its metal that its natural frequency of vibration is tuned to the frequency of the alternating current used. When so tuned the reed 202 will vibrate at the frequency of the alternating current with considerable amplitude. In order to make use of the vibrations of this reed for directing a movement of air, I provide a funnel-shaped shroud 222 surrounding the upper portion of the reed 202. This shroud 222 is supported by bracket 224 extending from the base 208. I have shown the shroud made with a straight taper having a comparatively large opening in the bottom and a larger opening in the top. However, other types of shrouds may be used if desired. This form of fan may be used in substantially the same manner as the one shown in Fig. 4.

In Figs. 2 and 3 a radial type of vibrating reed fan has been provided to make use of the natural vibrations of a sealed motor-compressor unit 111.

This sealed motor-compressor unit 111 is provided with a resilient mounting support 112 of some suitable type which will allow it to vibrate quite freely. This sealed unit 111 discharges into a condenser 115 having its tubing formed into a circular coil. This tubing is provided with cross-fins 117 which extend radially. Within this condenser structure are vibrating reeds 119 extending from a central post 121 like the spokes of a wheel. This central post 121 is fastened to and extends from the top of the sealed unit 111. As shown, there are provided three sets of blades 119 located one above the other. Each set of blades may be made from one piece of metal or from different strips of metal clamped together at their inner ends like spokes to the hub of a wheel. If desired, the reeds in the various sets may be staggered. The reeds should be of such a length and thickness that their natural vibration period or frequency is tuned to the frequency of vibration set up by the motor-compressor unit 111 in normal operation. If desired, the frequency of the different sets of blades may be different in order to cover a range of frequency vibrations of the unit. The vibration of the vibrating reeds 119 will discharge air radially through the circular finned condenser 115 which surrounds the reeds. In this way, the vibrations of the sealed unit form the motive power for vibrating the reeds which, in turn, circulate air between the fins of the condenser 115.

In this way, I have provided an efficient heat transfer system for the condenser of the refrigerating system and for interchanging heat between the primary evaporator and the food compartment.

While the form of embodiment of the invention as herein disclosed, constitutes a preferred form, it is to be understood that other forms might be adopted, all coming within the scope of the claims which follow.

What is claimed is as follows:

1. Refrigerating apparatus including liquefying means and evaporating means, each of said means including heat transfer means for interchanging heat with air outside of said means, and a vibrating reed-type fan means for circulating the air into heat exchange relationship with one of said heat transfer means.

2. Refrigerating apparatus including liquefying means and evaporating means, each of said means including heat transfer means for interchanging heat with air outside of said means, and a vibrating reed for circulating the air into heat exchange relationship with one of said heat transfer means, an electromagnet for applying impulses to said reed, and an alternating current source and a common circuit for supplying alternating current to said liquefying means and said electromagnet, said reed being tuned to the frequency of the alternating current.

3. Refrigerating apparatus including liquefying means and evaporating means, each of said means including heat transfer means for interchanging heat with air outside of said means, and a vibrating reed for circulating the air into heat exchange relationship with one of said

heat transfer means, an electromagnet for applying impulses to said reed, and an alternating current source and a common circuit for supplying alternating current to said liquefying means and said electromagnet, said reed being tuned to the frequency of the alternating current, said electromagnet being connected in electrical series relationship with said liquefying means.

4. Refrigerating apparatus including a compressor unit, a yieldable mounting for said compressor unit, said compressor unit having vibration characteristics causing it to vibrate upon its mounting, a condenser unit connected to said compressor unit, and a vibrating reed-type fan operated by the vibrations of the compressor unit for circulating air in heat exchange relationship with the condenser unit.

5. Refrigerating apparatus including a compressor unit, a yieldable mounting for said compressor unit, said compressor unit having vibration characteristics causing it to vibrate upon its mounting, a condenser unit connected to said compressor unit, and a vibrating reed-type fan operated by the vibrations of the compressor unit for circulating air in heat exchange relationship with the condenser unit, said fan having a natural frequency of vibration tuned to the vibration characteristics of said compressor unit.

6. In combination, a heat transfer member, a vibrating reed for circulating a fluid in heat exchange relation with said heat transfer member, electromagnetic means for applying impulses to said reed, means for supplying alternating current to said electromagnetic means, the natural frequency of vibration of said reed being in tune with the frequency of the alternating current.

7. Refrigerating apparatus including a refrigerant compressor unit, a yieldable mounting for said compressor unit, said compressor unit having vibration characteristics causing it to vibrate upon its mounting, a vibrating reed type fan including radially extending vibrating reeds mounted upon said compressor unit, a condenser connected to said compressor unit, said condenser being formed of tubing coiled about the free ends of the vibrating reeds and provided with substantially radially extending fins.

8. In combination, a heat transfer member, a vibrating reed type fan including a plurality of radially extending reeds for circulating a fluid in heat exchange relation with said heat transfer member, said heat transfer member being formed of tubing coiled about the free ends of said vibrating reeds, and means for applying impulses to said reed fan.

9. In combination, a heat transfer member, a vibrating reed type fan including a plurality of radially extending reeds for circulating a fluid in heat exchange relation with said heat transfer member, said heat transfer member being formed of tubing coiled about the free ends of said vibrating reeds and provided with radially extending fins, and means for applying impulses to said reed fan.

ANDREW A. KUCHER.
